CHILD'S TOILET SEAT

William J. Dunn, Winnetka, Ill., and Robert R. Richolt, Tujunga, Calif., assignors to General American Transportation Corporation, Chicago, Ill., a corporation of New York

Application August 30, 1946, Serial No. 693,834

7 Claims. (Cl. 4—239)

1

The present invention pertains to improvements in toilet seats for small children and has especial reference to toilet seats of the type having a confining framework, including side arms and a back rest, capable of movement from normal operative condition to a collapsed relation to the seat proper.

Generally stated, it is an object of the present invention to provide in a child's toilet seat a construction facilitating collapsing of the structure.

More particularly it is an object of the invention to provide a novel construction in the confining framework of a child's toilet seat whereby the framework may be collapsed automatically merely as an incident to the lifting of the seat into an out of the way position.

Another object of the invention is to provide means including extensible braces normally holding the arm rests and back rest in erected position relative to the seat member and being easily manipulable to effect collapsing of the structure.

A still further object is to provide a toilet seat embodying a novel attaching means for detachably installing the seat on an ordinary toilet assembly.

The objects of the invention thus generally set forth, together with other and ancillary advantages, are attained by the construction and arrangement shown by way of illustration in the accompanying drawings, in which:

Figure 1 is a perspective view of a child's toilet seat embodying the present invention and showing the same in erected condition ready for use in place on an ordinary toilet.

Fig. 2 is a fragmentary sectional view on a somewhat larger scale, illustrating the construction of a brace employed for holding the child's toilet seat in erected condition.

Fig. 3 is a fragmentary sectional view showing the relation of the parts as the main toilet seat is being raised and the auxiliary child's toilet seat attached thereto is about to be collapsed.

Fig. 4 is a perspective view of the child's toilet seat partially collapsed as it is swung upwardly into an out of the way position while remaining attached to the conventional toilet seat.

While the invention is susceptible of various modifications and alternative constructions, there is shown in the drawings and will herein be described in detail the preferred embodiment, but it is understood that it is not intended thereby to limit the invention to the form disclosed, but it is intended to cover all modifications and alternative constructions falling within the spirit and scope of the invention as expressed in the appended claims.

The present invention pertains to improvements in toilet seats for children of the general class as shown, for example, in the applicants' co-pending application Serial No. 549,316 filed Aug.

2

gust 14, 1944, now Patent No. 2,415,237, issued February 4, 1947.

Referring more particularly to the exemplary embodiment of the invention as illustrated in the drawings, it will be seen that the child's toilet seat there shown is adapted to be removably installed as an auxiliary attachment to a conventional adult toilet. As is customary the latter includes a generally oval or ring shaped main seat 10 and a lid 12. In brief, the attachment comprises a seat plate 16 having a generally central aperture 18 of suitably small dimensions for toileting a child, and a confining framework 19 mounted on the seat plate 16 through the medium of pairs of spaced parallel links 20 and 22, and including arm rests 24, a back rest 26 and a front guard 28. The links 20 and 22 are suitably pivoted to the seat 16 and arm rests at each side of the structure so as to form a parallelogram, and the front guard 28 is releasably connected to the upper ends of the two forward links 20.

The present invention concerns an improved means for holding the confining framework 19 in erected or operative relation to the seat plate 16, so constructed and arranged as to permit of easy and convenient manipulation when it is desired to collapse the device into a compact form capable of being accommodated between the main seat 10 and the lid 12 when both of these parts are swung into an upright position. Moreover, the invention provides means of a simple and effectual character for attaching the seat plate to the main toilet seat and providing a pivotal support for the seat plate.

Referring now to the drawings, the auxiliary seat plate is attached to the main seat 10 in a manner such as to permit swinging movement of the seat plate into and out of position concurrently with the main seat or independently thereof. Thus the auxiliary seat plate is provided with a pair of laterally spaced rearward extensions 30 and 31 having their extremities supported on pivot pins 32 and 33, herein formed as a part of a resilient clamping device 34 adapted for attachment to the main seat at the rear edge thereof. It will be observed that the projections 30 and 31 extend rearwardly to such a point that the axis of the pins 32 and 33 is in substantially vertical alignment with that of the hinge for the main seat 10 and lid 12. Thus when the auxiliary seat is not in use it can be swung upwardly into an out of the way position relative to the main seat 10 as shown in Fig. 4, or it can be swung upwardly with the main seat as shown in Fig. 3.

The novel clamping device 34 is preferably fashioned of resilient wire. The central section thereof is doubled back on itself to form a pair of rearwardly opening spaced clamping elements 35 and 36 adapted to grip the rear section of

main seat 10. The ends of the member 34 are bent so as to project laterally outwardly and form the pivot pins 32 and 33 which are journaled into bores in the seat projections 30 and 31. It is to be noted further that should it be desired to use the child's toilet seat temporarily, without attaching it to the main seat 10, member 34 can be swung around into a position rearwardly of back rest 26, as shown in dotted lines in Fig. 2.

The improved means for retaining the confining framework 19 in a normally erected relation to the seat plate 16 is so constructed as to permit easy and convenient collapse of the structure into such a thin configuration that it is adapted to remain in its out of the way position to expose the main seat 10 for unobstructed use. In the present instance this means is in the form of braces 40 interposed between the seat plate 16 and the confining framework 19 and susceptible of easy and convenient manipulation to permit the confining framework to be collapsed relative to the seat member or erected into operative condition. In the present preferred embodiment of the invention, each of the braces comprises a pair of telescoping members 41 and 42 respectively pivoted to one of the arm rests 24 and the seat plate 16, and interconnected so as to be held against movement in the erected position of the confining framework. As best shown in Fig. 2, the braces extend rearwardly and downwardly from the confining framework 19 to the extremities of the projections 30 and 31 on the seat plate 16.

The outer member 41 of each brace is preferably in the form of a tube having its sides flattened so that its cross section is that of a flat sided or more or less elongated ellipse. The upper ends of members 41 are pivotally connected to the confining framework 19 on pivot pins 43, which also serve as the pivotal connections between the upper ends of the rear links 22 and the arm rests 24.

The inner brace members 42 can be conveniently fashioned from any suitable sheet or bar stock and are dimensioned to slide freely in an endwise direction and to have an amount of fore and aft play within the tubular member 41. The inner ends of members 42 carry dogs 44 for engagement in notches 45 formed in the members 41, as shown in Figs. 2 and 3. The protruding lower ends of the members 42 are pivotally secured to the appropriate ones of the projections 30 and 31 of the seat plate 16 by the pivot pins 32 and 33.

When the confining framework 19 is in erected position, the dogs 44 on the members 42 are in latching engagement in the notches 45 in the members 41, and the confining framework is rigidly held in such position as illustrated in Figs. 1 and 2. When it is desired to move the child's toilet seat into its out of the way position, the seat plate 16 is merely raised upwardly, or both the seat 16 and the main seat 10 are raised upwardly together, and the connections 44, 45 are disengaged. Preferably the arrangement is such as to permit automatic disengagement of these connections as an incident to the raising of the seat plate 16. When the position illustrated in Fig. 3 is attained, the back rest 26 strikes the lid 12 of the conventional toilet assembly and is deflected upwardly relieving the frictional holding pressure between the dogs 44 and the upper sides of the notches 45. Also in this position the braces 40 have been moved slightly past a verti-

cal position so that the members 41 and 42 are free to swing rearwardly by the force of gravity, thereby disengaging the dogs 44 from their respective notches 45. As the seat plate 16 is raised further, the back rest 26 continues to slide upwardly along the lid 12, extending braces 40, and forcing forwardly links 22, arm rests 24 and links 20 until the entire confining framework 19 is collapsed into a thin configuration against the open lid 12 with the seat plate 16 lying substantially flat against the back rest 26 and between arm rests 24. Thus it can be seen that this complete collapsing action obtains automatically as an incident to the raising of the seat plate 16 into an out of the way position.

Should it be desired to collapse the confining framework 19 without raising the seat plate 16, the braces 40 can be quickly released by grasping the members 41 and raising them upwardly slightly. This action causes members 42 to be fulcrumed on the underside of members 41 at their lower ends at 41a, and thus the dogs 44 on the upper ends of members 42 are forced from engagement in the notches 45. The confining framework can then be swung forwardly and lowered onto the seat plate 16.

With the seat plate 16 in place on the main seat 10 and the confining framework 19 collapsed, all that is necessary to erect the framework so that the child's toilet seat becomes ready for use is to raise the back rest 26 and swing it rearwardly into position. The incident action is to bring the entire framework 19 into normally erected position and to telescope together members 41 and 42 of the braces 40. As this position is attained the dogs 44 drop into the notches 45 and thereby the confining framework is rigidly secured and the auxiliary seat is ready for use.

We claim as our invention:

40. 1. A child's toilet seat adapted for detachable mounting on an ordinary generally ring shaped toilet seat for adults, comprising, in combination, a seat plate dimensioned to overlie and rest upon the adult seat, and a resilient wire member having its central portion doubled back on itself to form clamping elements for gripping the rear section of said adult seat and having its ends projecting laterally outwardly, said seat plate being pivotally mounted on said projecting ends to permit said seat plate to be swung upwardly into an out of the way position.

2. A child's toilet seat adapted for use as an auxiliary attachment to a conventional adult toilet assembly, comprising, in combination, a generally centrally apertured seat plate, a collapsible confining framework mounted on said seat plate, attaching means adapted to detachably and pivotally secure the child's toilet seat to said adult assembly, and brace means including a pair of interengaging telescoping links extending between said confining framework and said seat plate for rigidly retaining said confining framework in erected position, said links being automatically disengageable as an incident to the raising of said seat plate into an out of the way position to effect the collapse of said framework.

3. A child's toilet seat adapted for use as an auxiliary attachment to a conventional adult toilet assembly, comprising, in combination, a generally centrally apertured seat plate having rearwardly extending projections, a confining framework supported on said seat plate, attaching means adapted to detachably and pivotally secure the child's toilet seat to said adult assembly, and brace means including a pair of

interengaging telescoping members secured respectively to said seat plate and said framework for rigidly retaining the framework in erected position, said members being automatically disengaged as an incident to the raising of said seat plate into an out of the way position, the inner of said telescoping members having a laterally projecting dog thereon adapted for latching engagement in a notch in the outer of said members, said inner member being pivotally connected at its protruding end to one of said seat plate projections and the outer member being pivotally connected to said confining framework.

4. A child's toilet seat adapted for use as an auxiliary attachment to a conventional adult toilet assembly including a main seat and a lid, said child's toilet seat comprising, in combination, a seat plate, a clamping member for detachably and pivotally securing the seat plate to said main seat, a confining framework mounted on said seat plate, and brace means including a pair of telescoping members adapted for latching engagement with each other and having their outer ends connected respectively to said confining framework and said seat plate, said brace means being effective when said members are engaged to retain said confining framework in erected relation to said seat plate, said members being releasable from latching engagement when said confining framework is deflected upwardly upon engagement with said lid when said seat plate is moved into an out of the way position.

5. A child's toilet seat adapted for use as an auxiliary attachment to an ordinary adult toilet assembly, comprising, in combination, a generally centrally apertured seat plate, means adapted to detachably and pivotally secure said seat plate to said adult assembly, a confining framework mounted on and adapted to be alternately supported in an erected or in a lowered relation to said seat plate, and extensible brace means including a pair of telescoping members interposed between said seat plate and said framework and having interengaging elements thereon for holding said confining framework in erected position, said elements being disengageable either automatically as an incident to the raising of said seat plate into an out of the way position or by fulcruming one of said members on the other to permit movement of said framework into its lowered position.

6. A child's toilet seat adapted for detachable mounting on a conventional adult toilet assembly comprising, in combination, a seat member, a confining framework and braces for supporting said confining framework in erected position, said braces including inner and outer telescoping members, the outer member being tubular and pivotally connected to said confining framework and having a notch adjacent said pivotal connection, the inner member being pivotally connected to said seat member and having a laterally projecting dog on the inner end thereof adapted for latching engagement in said notch in said outer member.
- 15 7. A child's toilet seat adapted for detachable mounting on an ordinary adult toilet assembly including a generally ring shaped seat and a lid adapted to occupy an upright position, said child's toilet seat comprising, in combination, a seat plate, a clamping member for removably securing the seat plate to said adult seat and providing a pivotal support for the seat plate, a collapsible confining framework mounted on said seat plate, and extensible braces including interengaging elements secured respectively to said seat plate and said framework and operative to rigidly hold the framework in erected relation to said seat plate, and means for automatically releasing said elements to collapse said framework as an incident to the engagement of the framework and the upright lid when said seat plate is raised into an out of the way position.
